UNITED STATES PATENT OFFICE

2,455,688

PORTABLE ELECTRIC STEAM RADIATOR

Philip S. Malickson, Philadelphia, Pa., assignor to
Sentry Safety Control Corp., a corporation of
Pennsylvania

Application February 11, 1947, Serial No. 727,927

1 Claim. (Cl. 219—38)

1

My invention relates to a portable radiator, electrically heated to create steam, whereby an office or a room in a home may be heated.

Heretofore, electric and gas heaters have been used in the home for warming chilly rooms and for supplementing the regular heating system. These prior art heaters, employing an exposed electric heating coil, or an open flame have a tendency to make the air extremely dry and irritating to the nasal passages. Frequently, too, they use needed oxygen and they impart a peculiar "burned" odor to the air which is not pleasant. It can be realized that the open flame, and the glowing resistance element are fire hazards, and may burn anyone coming in contact therewith.

A steam radiator provides a more gradual and uniform supply of heat, and if it can be made portable, is a better solution to the problem. Efforts have been made to use electricity for heating portable steam radiators, and have proved successful, except for the expensive construction employed.

It is an object of my invention to provide an electric-steam radiator which is inexpensively constructed from steel stampings.

Another object of my invention is to provide an electric-steam radiator whose heat capacity can be increased by increasing the number of stamped sections comprising the unit.

Another object of my invention is to provide a safe portable steam radiator having no dangerously hot parts or exposed sharp edges, and which is light enough to carry from room to room.

Another object of my invention is to provide a radiator comprised of individual sections bolted together to form a water-tight and a steam-tight unit.

A further object of my invention is to embody in a portable electric steam radiator a tell-tale indicator to show when the device is operating.

Other objects of my invention are to provide an improved device of the character described, that is easily and economically produced, which is sturdy in construction, and which is highly efficient in operation.

With the above and related objects in view, my invention consists in the details of construction and combination of parts, as will be more fully understood from the following description, when read in conjunction with the accompanying drawings in which:

Fig. 1 is a side elevational view of a portable steam radiator embodying my invention.

2

Fig. 2 is an end elevational view thereof.

Fig. 3 is a fragmentary sectional view taken along the line 3—3 of Fig. 1.

Fig. 4 is a fragmentary sectional view taken along the line 4—4 of Fig. 1.

Fig. 5 is a fragmentary sectional view taken along the line 5—5 of Fig. 1.

Fig. 6 is a sectional view of the preferred embodiment of my invention wherein each radiator section is formed from a pair of complementary male and female stampings.

Fig. 7 is a fragmentary side section showing the water-tight joint between the adjacent radiator sections.

Fig. 8 is a fragmentary side section of the lower portion of the radiator showing the heating element, and a concentric perforated tube whose end caps also serve to compress the radiator sections together.

20 Referring now in greater detail to the drawings, wherein similar reference characters designate similar parts, I show a portable radiator which has an electric heating coil therein and which may be used safely in the home as well as in such places as the bathroom, bedroom, recreation room, nursery, etc., and which will provide heat that does not absorb an excessive amount of oxygen or moisture from the air, which will emit no noxious odors, and wherein no sharp edges or dangerous parts are exposed.

25 The radiator comprises a plurality of adjacent hollow sections, generally designated as A, wherein water and steam are held. Each section is formed from a pair of complementary and identical steel stampings 10, 12. Each stamping has a vertical surface 13 with two dished flanges 13A and 13B having openings therein, and projecting outwardly on one side near the top and bottom, respectively. The edge 13C of the surface

30 35 is turned horizontally so as to form a hollow surface on the surface 13. The edge of the radiator section A is turned again to extend vertically a short distance 13D, whereby the radiator sections may be welded together, and the outermost edge portion 13E of the radiator is doubled back in order to be substantially parallel to the portion 13C in order to serve as a safety member.

35 40 When the stampings 10, 12 are assembled to form a section A, the vertical portions 13D abut, and are welded together. The edges 13E extend horizontally so that one cannot be injured by falling against the radiator.

45 50 The heating element consists of a coiled wire or ribbon 22 of electrical resistance metal, such as nickel-chrome alloy, stretched back and forth

upon ceramic spacers 24 within a closed metal cylinder 26. This cylinder extends through the lower flange 13B of each of the sections A.

In the preferred construction shown in Fig. 6, the two stampings 15 and 16 make up each radiator section, generally designated as B, and these stampings are complementary to one but not identical. The male stamping 15 has an upper, outwardly-extending flange 15A for steam to pass through to the adjacent radiator sections, and for a clamping rod 20 to pass through. Another outwardly-extending flange 15B is located in the lower portion of the stamping 15. The heating coil cylinder 26 extends through a metal retainer 28 and the perforated pipe 30. The flange 15B also permits water to pass between the adjacent radiator sections B. The female stamping 16 has inwardly-extending flanges 17A and 17B located at its top and bottom, respectively, which flanges are adapted to receive the male flanges 15A and 15B, respectively, of the adjacent stamping 15. The peripheral edges of these stampings are identical to the edges of the stampings 13, shown in Fig. 3, in that the edge is first turned horizontally away from the flanged side, then vertically a short distance, and finally back upon its horizontal portion. The vertical portions of the edge of each stamping 15, 16 form surfaces at which the adjoining stampings are welded together, and the horizontally-extending extreme edges provide a safe exterior for the radiator.

When the preferred radiator sections B are assembled together, flat sealing gaskets 18 are placed between the complementary flanges 15A, 17A and 15B, 17B, of the adjacent sections. A long bolt 20 passes axially through the upper flanges and compresses the sections B and the seals 18 together.

The heating coil 26 extends through the lower annular flanges of the radiator sections B. The heating coil jacket 28, as shown in Fig. 8, has a flange 29 at one end, and its length is encased in a perforated tube 30, which also has a flange 32 at one end and is threaded at its other end. The flanged ends of the jackets 28 and 30 are bolted to one end section 34 with seals 18 interposed for a water-tight and steam-tight joint. A filler cap 36 screws onto the threaded end of the perforated jacket 30 and its flanged edge is bolted to the other end section 35 through a seal 18. The opening of the filler cap is level with the top of the perforated jacket 30, so that the radiator can be filled with water only to the level consistent with rapid heating and efficient steam generation. A conventional plug 38 closes the filler cap opening.

The number of radiator sections used in making up a radiator unit depends upon the size of the room to be heated; for example, the radiator for heating a large area is composed of many more sections than a radiator used for heating a small space.

In operation, current is supplied to the heating coil, causing it to glow at a red heat. The heat is transmitted through the surrounding metal jacket 28 to the water, in the bottom of each section, generating steam. The rising steam imparts its heat to the radiator walls and falls condensed back into the water below. It can be seen that the heating coil is entirely protected, and the transfer of heat to the air is accomplished through several successive steps making for a gradual and uniform heat dissipation.

The ends sections 34 and 35 of each radiator section differs from the inner sections 10, 12 or 15, 16, in that they are formed with leg extensions 44, and are provided with tapped holes to receive the flange bolts.

The integrally formed legs on the radiator legs prevent the unit from falling if it becomes necessary to replace the heating coil.

A safety valve 46 is fitted into one end section near the top, and prevents dangerous pressures from being generated within the radiator. Actually the heating coil is of such wattage dissipation that with the normal heat radiation from the radiator walls it is almost impossible to generate a high steam pressure. Actually the radiator will function without water, and even if the device should be dry there will be no danger in its operation. In this case, of course, the heat is transmitted to the radiator walls mainly by conduction, and the enclosed air, and the efficiency is not as great as when the radiator is heated by convection currents of steam.

The electrical connections C to the heating coil are brought out through the flanged end of jacket 28, and have a tell-tale indicator 48, such as a red glow lamp, bridged across them, so that the indicator glows when the radiator is operating.

A carrying handle 50, made from iron rod or strap iron, and fitted with an insulated handle, is attached to the completed radiator.

Although my invention has been described in considerable detail, such description is intended as being illustrative rather than limiting, since the invention may be variously embodied, and the scope of the invention is to be determined as claimed.

I claim as my invention:

A portable electrically-heated steam radiator comprising complementary stampings which form radiator sections, the edges of said sections turned so as to present no exposed sharp edges, means for holding said sections together, means for circulating steam and water through said sections, an electric heating element in the base of said radiator for the purpose of heating said water, a carrying handle integrally formed with said radiator, means to indicate when the electric heating element is energized, means for preventing and for safeguarding against the development of excessive steam pressure within the radiator sections, and said complementary stampings of said radiator sections being nonidentical, one of said sections having an outwardly extending flange and its adjacent section having an inwardly extending flange, said flanges of adjacent sections interfitting with one another.

PHILIP S. MALICKSON.
